UNITED STATES PATENT OFFICE

2,072,200

SLIDE FASTENER

Raymond E. De Vore, Meadville, Pa., assignor to
 Joy Manufacturing Company, Franklin, Pa., a
 corporation of Delaware

Application January 24, 1935, Serial No. 3,357

11 Claims. (Cl. 24—205)

This invention relates to fasteners of the type in which rows of cooperating fastening elements are brought into interlocked relation and are separated through the operation of a slider which moves along such rows.

Briefly stated, the invention contemplates a slider of the type suggested having a deflecting plow located at the leading end of the slider and immediately below the adjacent fastening elements so as to move out of the way, papers and other articles which might otherwise be caught between the rows of fastening devices, to the end that the drawing together of the fastening elements is facilitated.

More specifically, the leading end of the deflecting plow will be found to extend straight across and approximately at right angles to the line of travel of the slider to points well under the adjacent fastener elements, so as to move out of the way articles which might otherwise be caught between the fastener elements and in addition, as is important to observe, the said leading end of the slider forms obtuse angles with the adjacent portions of the rows of fastener elements and thus avoids the creation of crotches in which papers or other articles may be caught.

Another aspect of the invention has to do with a deflecting plow located at what might be said to be the trailing end of the slider so that during the retraction of the slider for the obvious purpose of unhooking the fastener, the adjacent material, of whatever nature it happens to be, is moved out of the way and is thus prevented from interfering with free operation of the slider.

The arrangement herein disclosed contemplates a deflecting plow in which the forward end thereof is rolled or beaded, first, for easy and non-destructive contact with the adjacent material, and second, so that the same may contact the fastener elements with a minimum of resistance, particularly in cases where the slider is required to make sharp turns or bends, for example, at the corners of a brief case, or in following the contour of a person's body, in which case the pressure contact of the deflecting plow with the fasteners is temporarily increased, all without reducing the ease with which the slider and the associated fastening elements may be operated.

Also, it will be found that the deflecting plow, in addition to moving inward the material that would otherwise interfere with the bringing together of the fastening elements, the same is positioned to lift or move outward those fastener elements that are immediately in advance of the slider or as might be otherwise expressed, the

material initially between the fasteners is moved in one direction and the fasteners are moved in the opposite direction or outward therefrom to clear the fasteners preparatory to the union thereof with the result that the slider may be advanced in a highly convenient and expeditious manner and without the annoyance that is so often due to the presence of protruding objects between the rows of fastening elements.

The invention forming the subject of this application may be incorporated in a slide fastener of conventional or other design without material alteration in the design of such fasteners and without departure from established production methods.

Another aim of the invention is to provide a slide fastener of the character specified which is inconspicuous, durable, and which might be embodied in a slider with but a negligible increase in cost.

Other objects and advantages will be apparent during the course of the following description.

In the accompanying drawing forming a part of the application, and in which like numerals are employed to designate like parts throughout the same,

Figure 1 is a fragmentary edge elevation of a receptacle, possibly a brief case, having a slide fastener embodying the invention, the slide fastener being partly open,

Figure 2 is a fragmentary side elevation of the structure shown in Figure 1,

Figure 3 is a vertical transverse sectional view taken on line 3—3 of Figure 2,

Figure 4 is a perspective of a slider embodying the invention,

Figure 5 is a perspective of the slider taken from the other side,

Figure 6 is a fragmentary plan of a slide fastener embodying a modification of the invention,

Figure 7 is a sectional view taken on line 7—7 of Figure 6,

Figure 8 is a perspective of a slider embodying another modification of the invention,

Figure 9 is a fragmentary side elevation of a slide fastener embodying a further expression of the invention,

Figure 10 is a fragmentary plan view of the matter shown in Figure 9,

Figure 11 is a perspective of the slider featured in Figures 9 and 10.

In the drawing, the numerals 5 designate rows of cooperating fastening devices or chains, having individual fastener elements 8 which, of

course, are provided with conventional or other interlocking means. Such rows of fastening devices are shown to have the customary attaching tapes by which the same may be attached to the edges of an opening to be closed. The opening may be in a garment, a tent, a pocketbook, a brief case, a receptacle, or any of the numerous articles to which slide fasteners may be adapted. By way of example, the invention is shown in connection with a receptacle in the nature of a brief case 10.

The slider is designated by the numeral 12 and as shown in Figure 4 is provided with channels or runways 14 which converge in a single passage for the fastener elements 8. Of course, as is well-known in this art, the slider provides a means by which the fastener elements are brought into interlocking relation and are separated.

As brought out in the opening paragraphs of this specification, it has been found that the articles immediately beneath the rows of fastening devices occasionally extend up between the spaced rows of fastening devices and interfere with the free advance of the slider. For example, in a brief case, papers sometimes project into the space between the fasteners, when separated, of course, and are chewed through the operation of the slider. Also, when the slider is used on a garment, the material immediately inward thereof or possibly the flesh of a person, becomes pinched between the rows of fastener elements and this, of course, is to be avoided without at the same time, forming other angles or crotches conducive to the pinching or squeezing of the adjacent material or flesh and to this end the slider shown herein will be found to have a deflecting plow 20.

As shown in Figure 4, the deflecting plow 20 extends forwardly from the underside of the slider and has the forward terminal portion thereof beaded as indicated at 24 so as to define inwardly and outwardly directed material and fastener engaging ribs respectively. The ribs thus formed have smooth rounded surfaces for sliding contact with protruding articles and the under surfaces of the fastener elements immediately above.

More particularly, the upwardly directed rib of the beaded forward end of the plow is shown to be inclined from points spaced laterally of the central line of the plow to define oppositely located shoulders which underlie and engage the adjacent fastener elements and which serve to definitely turn outward or lift these fastener elements in the direction opposite the material immediately below the fastener.

It will be seen that the slope of the shoulders 25 has the effect of turning upward and outward the adjacent fastener elements, and in fact, the 30 inclination of these shoulders determines the extent to which the fastener elements are turned outward.

In other words, the deflecting plow serves the dual purpose of moving inward the material 35 which would otherwise lodge between the rows of fastening elements and at the same time, turning outward the fastener elements immediately in advance of the slider, so as to allow such fastener elements to be brought easily 40 together.

It is important to observe that the deflecting plow 20 and more particularly, the extreme forward portion thereof extends laterally beyond or outward of the adjacent fastener elements a distance ample to avoid engagement of the corners 45

of the plow with the free terminal portions of the adjacent fastener elements.

As shown in Figure 1, the leading terminal of the deflecting plow extends straight across or approximately at right angles to the line of travel 5 of the slider and forms obtuse angles with the adjacent portions of the rows of fastener elements. By this arrangement, there is avoided the creation of acute angles or crotches or notches, in which material might lodge. If the leading 10 portion of the deflecting plow were formed with a bowed forward portion as in the case of the patent to Rust, No. 1,886,123, there would be defined highly objectionable pockets or notches conducive to the collection of material. A deflecting plow or guard which actually forms acute 15 angles or crotches with the adjacent portions of the rows of fastening devices, defeats its purpose. The presence of notches or crotches immediately 20 in advance of the slider actually encourages interference on the part of book leaves, clothing and other articles with the free operation of the slider.

As shown in Figure 2, the inclined shoulders of the deflecting plow 20 remain in constant sliding 25 contact with the undersides of the fastener elements 8 and are rounded for easy operation, particularly where the slider is caused to make a turn. It has been found that a slider equipped with the herein disclosed deflecting plow makes 30 relatively sharp turns with great ease, the shoulders of the plow remaining at all times in smooth sliding contact with the undersides of the fastener elements. Of course, when the slider is required to make a turn, the pressure contact between the 35 plow and the fastener elements is temporarily increased but it has been found in actual practice that this does not add in an appreciable way to the effort required for movement of the slider.

It is illustrated in Figures 4 and 5 that a deflecting plow 30 extends rearwardly from the underside of the trailing or rear end of the slider and has the rear terminal portion thereof beaded as indicated at 35. The beaded portion 35 defines an inwardly directed rib which will be found to 40 have a smooth rounded surface for sliding contact with protruding objects. In this way, the objects encountered by the beaded portion 35 are moved 45 out of the way and are prevented from interfering with free retraction of the slider.

In the form of invention disclosed in Figures 6 and 7, the slider is designated by the numeral 50 and is formed with a main passage having diverging branches which, as is well-known in the art, provide for the bringing together and the separation of the fastener elements of the complementary rows.

It is clearly illustrated in Figure 7 that the forward portions of the diverging passages through the slider are turned or tilted upward 60 and outward at the inner portions thereof at acute angles, possibly 45°. This transverse tilting of the slider branches has the effect of turning the fastener elements therein and immediately in 65 advance of the slider upward and outward away from the material beneath the slider.

In explaining just why the fastener elements immediately in advance of the slider are turned outward, it is pointed out that the fastener elements are rigidly secured to the inner edge portions of the associated tapes close enough to each other to have the effect of stiffening the adjacent portions of the tapes. Hence, when the fastener elements and the portions of the tapes within the diverging passages of the slider are turned out- 70 75

ward, the fastener elements immediately in advance of the slider will also be turned outward. In other words, there is a cooperation between the slider and the adjacent portions of the types locking to the outward turning of the fastener elements immediately in advance of the slider.

Of course, the slider shown in Figures 6 and 7 is equipped with a deflecting plow which may be similar to the plow 20 so that the protruding material of whatever nature it happens to be, is moved inward while the slider itself is provided with means to turn outward the fastener elements and thus establish positive clearance for the free bringing together of the fastener elements which might otherwise become entangled with projecting objects.

In the form of invention illustrated in Figure 8, the slider 60 is of the same general construction as the slider shown in Figures 1 to 5 except that 20 the beaded forward terminal portion 64 of the plow has a straight upper surface as distinguished from the sloping shoulders so prominently featured in Figure 4.

In the form of invention disclosed in Figures 9 25 and 10, the slider is designated by the numeral 70 and is shown to be formed with a fastener passage having converging branches to bring together and to separate the fastener elements of the complementary rows.

30 In this form of invention, the outer or open terminal portions of the branches of the slider are turned upwardly and outwardly at approximately 90° or perpendicular to the plane of the slider. By this arrangement, the fastener elements encountered by the converging branches of the slider are turned outward with the result that the slide fasteners immediately in advance of the slider are also turned outward approximately the same extent away from the material, 40 of whatever nature it happens to be, immediately inward of the rows of fastener elements.

In addition, the slider 70 is formed with a deflecting plow 14 extending an appropriate distance beyond the slider and positioned for lifting engagement with the inner surfaces of the fastener elements so as to cooperate with the twist of the branches of the slider in turning the fastener elements outward. Of course, as in the case 45 of the plow 20, the forward or leading portion of the plow may be beaded first for the purpose of moving protruding objects inward away from the fastener elements and the advancing slider and second to cooperate with the twisted branches 50 of the slider in turning the adjacent fastener elements outward or away from the material beneath the slide fastener.

In the form of invention shown in Figures 9 and 10 the plow 14 has the upper surface thereof straight as distinguished from having sloping shoulders such as are indicated by the numeral 60 25 in Figure 4.

Having thus described the invention what is claimed is:

1. In a slide fastener, rows of cooperating fastener elements, a slider having means to draw the fastener elements of the cooperating rows into interdigitating relation and to separate the same, and a deflecting plow carried by the slider and having a leading portion extending entirely 65 across the space between and beneath the rows of fastener elements in advance of the slider.

2. In a slide fastener, rows of cooperating fastener elements, and a slider having means to draw the fastener elements of the cooperating 70 rows into interdigitating relation and to separate

the same, and a deflecting plow carried by the slider and having a leading portion extending beneath the rows of fastener elements at obtuse angles to the adjacent portions of said rows, said deflecting plow being provided with means engaging and lifting the fastener elements immediately 5 beyond the slider.

3. In a slide fastener, rows of cooperating fastener elements, and a slider having means to draw the fastener elements of the cooperating rows 10 into interdigitating relation and to separate the same, and a deflecting plow carried by the slider and having a leading portion extending beneath the rows of fastener elements at obtuse angles to the adjacent portions of said rows, said deflecting 15 plow being provided with inclined shoulders engaging and turning outward the fastener elements immediately beyond the slider.

4. In a fastener for use in connection with flexible 20 rows of cooperating fastener elements, a slider having means to draw the fastener elements of the cooperating rows into interdigitating relation and to separate the same, and a deflecting plow carried by the slider and having a straight 25 leading portion extending entirely across the space between and beneath the rows of fastener elements in advance of the slider and being disposed at angles to the adjacent portions of said rows greater than right angles.

5. In a fastener of the type having flexible 30 rows of cooperating fastener elements, a slider having diverging channels for the reception and passage of the fastener elements, and a deflecting plow carried by the slider and having a leading portion extending above the plane of the 35 bottom of said channels and beneath the fastener elements in lifting association therewith to raise the same and extending in a straight line substantially at right angles to the line of travel of the slider.

6. In a fastener of the type having flexible 40 rows of cooperating fastener elements, a slider having means to draw the fastener elements of the cooperating rows into interdigitating relation and to separate the same, and a deflecting 45 plow carried by the slider and having a leading portion extending beneath the fastener elements and in constant engagement therewith and extending on a substantially straight line at right angles to the line of travel of the slider, and a second deflecting plow carried by the slider and projecting beyond the rear end thereof.

7. In a slider for use in connection with rows 50 of cooperating fastening elements, a body having means to bring together and to separate rows of fastener elements, and a deflecting plow extending beyond one end of the slider and having a bead defining inwardly and outwardly directed ribs, the inwardly directed rib being projected beneath the surface of the plow for engagement with objects inward of the fastener elements while the outer rib is extended outwardly of the outer surface of the plow for sliding engagement with the fastener elements immediately in advance of the slider to turn outward such fastener elements.

8. The construction set forth in claim 7, said slider being provided with means therein cooperating with said outwardly directed rib to turn outward the fastening elements immediately in advance thereof.

9. In a slide fastener, rows of cooperating fastener elements, and a slider having means to draw the fastener elements of the cooperating 75

rows into interdigitating relation and to separate the same, and a deflecting plow carried by the slider and having a leading portion extending beneath the rows of fastener elements and 5 formed with inclined shoulders engaging and turning outward the fastener elements immediately beyond the slider.

10. In a slider for use in connection with rows of cooperating fastener elements for attachment 10 to an article, a longitudinally movable slider body having a passage formed with diverging branches, said branches being provided with means for turning the fastener elements entering the slider and immediately in advance of the 15 slider outwardly with respect to the line of travel of the slider and in a direction away from the

article to which the fastener elements are attached, and a deflecting plow carried by the slider and having a leading portion extending above the plane of the bottom of said branches and beneath the rows of fastener elements in 5 lifting association therewith.

11. A fastener of a type having flexible rows of cooperating fastener elements, a slider having diverging channels for the reception and passage of the fastener elements, and a deflecting plow 10 carried by the slider and having a leading portion extending above the plane of the bottom of said channels and beneath the fastener elements in lifting association therewith to raise the same. 15
